UNITED STATES PATENT OFFICE.

GEOEGE W. CHESBROUGH, OF ROCHESTER, NEW YORK.

SOFT-SOLED SHOE.

1,123,245.

Specification of Letters Patent.

Patented Jan. 5, 1915.

Application filed September 6, 1913. Serial No. 788,432.

To all whom it may concern:

Be it known that I, GEORGE W. CHESBROUGH, of the city of Rochester, in the county of Monroe and State of New York, have invented certain new and useful Improvements in Soft-Soled Shoes; and I do hereby declare the following to be a full, clear, and exact description of the same, reference being had to the accompanying drawings, forming a part of this specification, and to the reference-numerals marked thereon.

My invention relates to soft soled shoes, more particularly infants' shoes.

A prime object of the invention is to provide a shoe of this type, having the attractive finished appearance of a welt shoe, while being in reality produced by a simpler and cheaper process of the general character employed in the production of "turned shoes" and of soft yielding material throughout.

A further object is to produce an infant's shoe of artistic design at low cost and not requiring the use of special machinery in the manufacture.

The above and other objects and features of the invention will be better understood from the following detailed description in connection with the accompanying drawings and will be thereafter pointed out in the appended claim.

Referring to the drawings: Figure 1 is a perspective view of a shoe constructed in accordance with my invention; Fig. 2 is a transverse section through the forward part of the shoe; Fig. 3 is a perspective view showing the shoe before it is turned; Fig. 4 is a transverse section similar to Fig. 2 and showing the shoe before turning, and Fig. 5 is a perspective view showing the parts of the sole assembled before being united with the upper.

The outer sole, 10, preferably formed of a piece of kid or other soft leather, is united to an inner sole element 11, preferably of felt or other soft material, by peripheral stitching 12, there being desirably a filler piece 13 of thick paper or other suitable

material interposed between these parts and extending out to near the line of stitching 12, as shown.

In accordance with my invention, I form the inner sole element or felt piece 11, with a peripheral extension 14 projecting all around some little distance beyond the outer sole 10. In assembling the upper 16 with the sole, this projecting portion 14 is bent down as seen in Fig. 4 and the lower edge of the upper 16 is stitched thereto as seen at 15, these parts being thus in position for convenient stitching on an ordinary sewing machine. The shoe is now "turned"—i. e. reversed from its shape in Figs. 3 and 4 to that of Figs. 1 and 2, when the projecting edges of the upper end of the inner sole extension 14 are concealed inside the shoe, as seen in Fig. 2, while the inner sole extension 14, showing as a strip or rib between the outer sole 10 and the upper, presents the appearance of a welt, as in a welt shoe adding to the artistic finish of the shoe and being in reality a strong and reliable assemblage of the shoe parts.

It is to be observed that my improved shoe can be cheaply produced without any of the elaborate machines required for shoe manufacture, since both of the stitching lines 12 and 15 which complete the assemblage of the shoe parts, can be made on an ordinary sewing machine. I consider the use of an inner sole of felt or like material with its projecting peripheral edge 14 to be a valuable and important feature, since the felt presents a soft surface to the foot and is cheaper than leather, as well as being readily obtained commercially, of a uniform thickness. Further, the rib facing of felt presented in the similitude of a welt in the finished shoe, makes a particularly pleasing and attractive appearance as an article of sale.

I do not desire to be limited to the precise embodiment of the invention shown, as to details of construction and refer to the appended claim, rather than to the foregoing description to indicate the scope of the invention.

I claim as my invention:
A shoe comprising an outer sole, an inner sole of soft material secured to said outer sole and having its entire peripheral edge 5 portion turned upwardly, forming a narrow strip for the attachment of a shoe upper, the edge of said strip being turned inwardly,

and a shoe upper having its lower edge turned inwardly and secured by stitching to the inwardly turned edge of said strip.

GEORGE W. CHESBROUGH.
